[57] **CLAIM**

The ornamental design for wheel center, as shown and described.

DESCRIPTION

FIG. 1 is a front elevational view of a wheel center showing my new design;

FIG. 2 is a side elevational view thereof;

FIG. 3 is a rear elevational view thereof;

FIG. 4 is a cross-sectional view thereof taken along line 4—4 in FIG. 1;

FIG. 5 is a front elevational view of a wheel center showing a second embodiment of my new design, the difference being in the omission of a wheel bolt opening and the arrangement of the wheel bolt openings shown herein;

FIG. 6 is a rear elevational view of FIG. 5; and

FIG. 7 is a side elevational view of a wheel center showing a third embodiment of my new design, the sole difference from FIG. 1 embodiment being in the height thereof.

The broken lines in FIGS. 1 and 2 of the drawings are for illustrative purposes only.
